UNITED STATES PATENT OFFICE.

JAMES M. CARTWRIGHT, OF CLARKSDALE, MISSISSIPPI.

RADIO RECEIVING CIRCUIT.

Application filed November 5, 1924. Serial No. 747,961.

This invention relates to improvements in radio receiving circuits and it consists of certain novel arrangements and combinations herein described and claimed.

5 An object of the invention is to provide a variable resistance in the ground for the purpose of overcoming objectionable radio frequency oscillations originating either in the receiver itself or being imposed upon the 10 receiver by external impulses.

A further object of the invention is to provide a radio receiving circuit employing a variable resistance in the ground for the purpose of varying the potential of the grid circuit 15 in a manner clearly brought out below, thereby to more readily accommodate the incoming waves.

Another object of the invention is to provide a radio receiving circuit employing a 20 plurality of stages of radio frequency amplification, the connections in the circuit of one of these stages being such that it is operated as a frequency changer.

25 Other objects and advantages appear in the following specification, reference being had to the accompanying drawing which is a diagram of a radio receiving circuit incorporating improvements.

30 The diagram illustrates a 5-tube circuit. The first four of these tubes, respectively designated RF¹, RF², RF³ and RF⁴, constitute four stages of tuned radio frequency amplification, the last tube 5 being employed as a detector. As indicated in one of the foregoing 35 objects of the invention the third stage RF³ is operated as a frequency changer in addition to its amplifying function, because it is made to control pulsations of both radio and audio frequency.

40 Each of the four stages mentioned includes an air-core transformer. These are respectively designated 6, 7, 8 and 9. Use is made of a tuning element 10 which may be a transformer of a type identical with 6, 7, etc. Each 45 of the respective transformers, including the tuning transformer 10, has a variable condenser for the purpose of tuning thereby identifying the circuit as being of the tuned 50 radio frequency type. These condensers are designated 11, 12, 13, 14 and 15, following the order of the foregoing description.

A lead 16 connects the antennæ with one side of the primary of the tuning transformer 10. A common negative wire 18 is connected to the opposite side of the primary. This wire connects with a binding post 19

which is herein regarded as the negative terminal of the A-battery. The positive terminal of the A-battery is connected to the binding post 20, and to this, in turn, is connected 60 the common positive wire 21. A rheostat 22 furnishes a control for the A-battery current.

It is to be noted that the filament of the stages or tubes RF¹, RF² and RF⁴ are connected with the common positive wire 21, the 65 opposite ends of these filaments being connected with the common negative wire 18. In respect to the stages or tubes RF³ and the detector 5 the negative ends of the filaments, are connected with the common negative wire 18 but the positive ends are connected with an auxiliary positive wire 23 which ultimately communicates with the common positive wire 21 but has an independent rheostat control 24.

70 This arrangement serves to carry out a particular purpose: The grid returns of stages RF¹, RF² and RF⁴ are connected to the common negative wire 18, in other words the filament minus circuit, by means of wires 25, 26 75 and 27. But the grid return of the stage RF³ and the detector 5 is connected by means of wires 28 and 29 to the filament plus circuit, in other words the auxiliary common positive wire 23. By virtue of connecting the 80 grid return of stage RF³ to a positive conductor, instead of to a negative conductor as in stages RF¹, RF² and RF⁴, the grid return circuit of stage RF³ is opposed, thereby neutralizing the foregoing circuit of RF¹, RF² 85 and RF⁴ by a decided back pressure. This 90 back pressure can be traced to occur in the A-battery itself.

A wire 30 connects the ground binding post 31 with the common negative wire 18. 95 But it is important to observe that a variable resistance 32 is interposed in the wire. The use of such resistance furnishes an important function of the improved receiving circuit because it is by such use that objectionable 100 radio frequency oscillations can be entirely eliminated from the circuit. It is by means of this resistance that the regenerating effect of the tubes in the radio frequency stages can be nullified. It also provides a control of the circuit in respect to oscillations originating at external sources, because undesired oscillations can be kept out of the circuit by properly manipulating the variable resistance. 105 The grid circuit of stage RF³ has a variable leak 33 and fixed condenser 34. The other radio frequency stages do not employ either 110

the variable grid leak nor the fixed condenser. The detector 5 has a fixed grid leak 35 and condenser 36.

Two distinct B-battery voltages are impressed upon the plate circuits of the various tubes. The positive terminal of a B-battery of $67\frac{1}{2}$ volts is connected to the binding post 37 from which it is distributed in common by a wire 38 to the plates of the 10 stages RF^1 , RF^2 and RF^4 through branch wires 39, 40 and 41. The positive terminal of a 45-volt B-battery is connected with the binding post 42 from which it is distributed in common by a wire 43 and branches 44 and 45 15 to the plates of the stage RF^3 and the detector 5. Two B-batteries are spoken of, but in practice use can be made of a single battery or an appropriate combination of B-batteries as is not uncommon in practice. The negative 20 B-battery terminal is connected at the binding post 46 which also has a connection with the negative A binding post 19. A maximum plate voltage of 45 volt B-battery is applied at binding post 42 only when hard tubes are 25 used in detector 5 and RF^3 . Such tubes are recommended.

The operation is as follows: It has already been pointed out that the grid returns of stages RF^1 , RF^2 and RF^4 are connected in the 30 filament minus circuit represented by the common negative wire 18, but that the grid return of stage RF^3 and of the detector 5 are connected to the filament plus circuit, represented by the auxiliary wire 23. The tubes of stages RF^1 , 35 RF^2 and RF^4 operate on $67\frac{1}{2}$ plate voltage by virtue of being connected with the wire 38, while the tube of stage RF^3 and the detector 5 operate on the lower plate voltage of 45 volts by virtue of being connected with the wire 43.

40 When a radio frequency impulse is impressed on the circuit through the tuning transformer 10 and is amplified in the radio frequency transformers 6 and 7 the condenser 34 begins to charge the same as in an ordinary detector action. The resistance 33 prevents the accumulation of negative voltage upon the grid of the tube in stage RF^3 , permitting it to leak off through the filament circuit including the auxiliary wire 23.

50 As the frequencies of the different wave lengths vary, the negative potential of the grid 33 also varies with the frequencies. There must obviously then be some method of varying the leakage of the resistance 33 in 55 order to prevent an entire blocking of the grid circuit in stage RF^3 , but at the same time allowing the modulated audio frequency waves to leak off at the proper moment.

It is here that the function of the variable 60 resistance 32 begins. As stated before, this resistance is placed in the ground circuit or lead 30, providing a proper path and control for the foregoing radio frequency carrier waves, of stage RF^3 . It is thus that the blocking of the tubes is prevented, eliminat-

ing undesired tube oscillations. The same action takes place in the detector tube 5 in conjunction with the condenser 36, resistance 35 and variable resistance 32.

The tube of stage RF^3 is actually doing a 70 double duty by passing waves at radio frequencies and rectifying them to audibility. Stage RF^4 is passing waves at radio frequencies only. Tube RF^3 has an output of waves at both radio and audio frequencies to stage 75 RF^4 , which as stated, passes only waves at radio frequencies. The result is the imposition of audio frequency waves upon radio frequency waves constituting a new radio frequency which is passed on to tube RF^4 for 80 amplification at radio frequencies, before being passed on to detector 5 for rectification to audibility at its output.

The rectification of a radio frequency impulse results, theoretically, in a smoother 85 modulated curve for the waves. The effect, then, of the action of the tube RF^3 is to smooth out the curve of a given wave and delivering the smooth wave to the tube RF^4 for amplification. The result is an audio wave of 90 smoother and greater regularity when delivered at the output of the detector 5. Another result is the marked decrease of atmospheric and local interference.

It is quite commonly known that receivers 95 employing radio frequency amplification through multiple stages are hard to control by virtue of being very unstable. Resistances of various kinds are commonly employed with an attempt at stabilization. This expedient has 100 had varying degrees of success. The circuit herein disclosed seeks to get at the desired result by different methods. The grid return of tube RF^3 is in the positive A-circuit (wire 23) while the other radio frequency tubes 105 RF^1 , RF^2 and RF^4 have the grid returns in the negative A-circuit (wire 18). The grid return of tube RF^3 is thus opposed to the grid return circuits of tubes RF^1 , RF^2 and RF^4 . This sets up a neutralizing effect by 110 virtue of the electrical back pressure spoken of before.

In addition to the setting up of this electrical back pressure in the circuit further 115 resistance to the free passage of radio frequency waves is offered by lowering the plate voltage of tube RF^3 from $67\frac{1}{2}$ to 45 volts. This furnishes a smaller electronic path.

It may be stated that this circuit contemplates the use of a loop aerial, a loop control 120 jack being employed as is quite common in practice.

I claim:—

1. In a radio receiving system including a plurality of tuned radio frequency amplifying stages arranged in cascade relation, and each stage including a three electrode tube, a detector tube coupled for rectifying the output of the amplifying stages, and an adjustable grid leak arranged in the grid-filament 125 130

circuit of a tube previous to the last radio frequency amplifying stage.

2. In a radio receiving system including a plurality of tuned radio frequency amplifying stages, each stage including a three electrode tube, a detector tube coupled for rectifying the output of the amplifying stages,

an adjustable grid leak in the grid-filament circuit of a tube preceding the last amplifying stage, and a positive bias connection for the grid return circuit of the tube having the adjustable grid leak. ¹⁰

JAMES M. CARTWRIGHT.
